(57) **CLAIM**

The ornamental design for a device for metal deposition, as shown and described.

DESCRIPTION

FIG. 1 is a front view of a device for metal deposition showing my new design.

FIG. 2 is a rear view thereof.

FIG. 3 is a top view thereof, a bottom view thereof having no ornamental features contributing to the design.

FIG. 4 is a left side view thereof.

FIG. 5 is a right side view thereof.

FIG. 6 is a first perspective view thereof.

FIG. 7 is a second perspective view thereof.

FIG. 8 is a front view of another embodiment of the device for metal deposition.

FIG. 9 is a rear view thereof.

FIG. 10 is a top view thereof, a bottom view thereof having no ornamental features contributing to the design.

FIG. 11 is a left side view thereof.

FIG. 12 is a right side view thereof.

FIG. 13 is a first perspective view thereof; and,

FIG. 14 is a second perspective view thereof.

The broken lines in the drawings and the areas surrounded thereby depict unclaimed environmental subject matter.
